NASAL MASK

Walter M. Boothby and Arthur H. Bulbulian,
Rochester, Minn., and William Randolph Lovelace, II, Albuquerque, N. Mex.

Application July 14, 1947, Serial No. 140,259
Term of patent 14 years

(Cl. D83—1)

To all whom it may concern:

Be it known that we, Walter M. Boothby, William Randolph Lovelace II, and Arthur H. Bulbulian, citizens of the United States, the said Boothby and Bulbulian residing at Rochester, in the county of Olmsted, State of Minnesota, and said Lovelace residing at Albuquerque, in the county of Bernalillo, State of New Mexico, have invented a new, original, and ornamental Design for Nasal Mask, of which the following is a specification, reference being had to the accompanying drawing, forming part thereof.

Fig. 1 is a top plan view of our nasal mask, showing our new design.

Fig. 2 is a bottom plan view showing the mask of Fig. 1 from the opposite side.

Fig. 3 is an end elevational view taken toward the open end of the tube shown in the mask of Fig. 1.

Fig. 4 is a side elevational view of the mask of Fig. 1.

Fig. 5 is an end elevational view of the mask of Fig. 1 taken toward the opposite end from Fig. 3.

We claim:

The ornamental design for a nasal mask, substantially as shown.

WALTER M. BOOTHBY.
ARTHUR H. BULBULIAN.
WILLIAM RANDOLPH LOVELACE, II.
